UNITED STATES PATENT OFFICE.

MELVILLE E. PETERS, GEORGE H. FATH, AND ALBERT F. MILLER, OF DENVER,
COLORADO.

EXTENSION-EDGE-BOX-BLANK-WRAPPING MECHANISM.

1,226,996.

Specification of Letters Patent. Patented May 22, 1917.

Application filed April 28, 1916. Serial No. 94,205.

To all whom it may concern:

Be it known that we, MELVILLE E. PETERS, GEORGE H. FATH, and ALBERT F. MILLER, citizens of the United States of America, residing in the city and county of Denver and State of Colorado, have invented a new and useful Extension-Edge-Box-Blank-Wrapping Mechanism, of which the following is a specification.

10 Our invention relates to improvements in extension edge box blank wrapping mechanism for box wrapping machines and the objects of our invention are:

First, to provide a box end and at the same time extension edge box wrapping mechanism that is so co-operatingly constructed within itself that both the extension edge wrapping wipers and the box end surface wipers are locked together and are moved together to engage the terminal ends of the blank and fold it up against the extension edge of the opposite ends of the box with a wrapping pressure. And

Second, to provide a quick, positively operating extension edge and vertical wall blank wrapping mechanism that while especially designed to be used for the opposite ends of boxes can nevertheless be adapted for, and be used for wrapping the sides of blanks 30 against the side extension edges and the sides of boxes.

We attain these objects by the mechanism illustrated in the accompanying drawings, in which:

35 Figure 1 is a vertical, longitudinal sectional view of a portion of a box wrapping machine equipped with the improved extension bottom box end wipers, the said wipers being swung to a horizontal position.

40 Fig. 2 is a side elevation of one of the said end wipers in a vertical position, showing the extension wiper or blade in position to press the blank over the extension ends of the bottom of the box, the end wiper being 45 shown in raised position in dotted lines.

Fig. 3 is a plan view of Fig. 2.

Fig. 4 is an end elevation of Fig. 2.

Fig. 5 is a horizontal sectional view on the line 5—5 of Fig. 4.

50 Fig. 6 is an edge view of a portion of one of the rack bars which operate the end wipers.

Fig. 7 is a plan view of the supporting slide block for the wiper head. And

Fig. 8 is a plan view of a blank for an 55 extension bottom box.

Our present invention is especially adapted for use on our multiple stage box wrapping machine, which is now pending in the United States Patent Office and was filed 60 November 5, 1915, Serial Number 59,860. Our invention, however, contemplates its use on all other box wrapping machines to which it can be adapted.

In illustrating our invention we have 65 shown it in connection with certain features of the first stage of our above named box wrapping machine, such as the plungers 1 and 2, the table 3, the side frames 4, the base plate 5, and the main driving shaft 6, and 70 other parts hereinafter mentioned. The blanks 7 are coated with gum on one side by any suitable means, but preferably by our improved blank gumming machine now pending, Serial Number 30,471, filed May 75 25, 1915.

Each of the end wiper supports is slidably mounted in a supporting block 8, which is provided with a hub portion 8^a that is pivotally mounted on a pin 9, that extends 80 through the ends of a yoke-shaped bracket 10. This yoke-shaped bracket stands in substantially a vertical position on the machine, and it is provided at its lower or closed end with an extended vertical plate 11, that is 85 bolted to one side of a slideway block 12, which is adjustably secured to a slotted plate 13, which is slidably mounted in the table 3. The lower end of the block 8 swings on its pivotal pin 9 down between the arms of the 90 yoke-shaped bracket, and during its operative movement it is swung from a normal horizontal position into a vertical position. This wiper supporting device comprises 95 two parts or pieces, which act independent of each other during the different stages of wrapping the end flaps against the opposite ends of the box. One of these parts is the block 8, which pivotally swings in the yoke-shaped bracket 10; the other part is the 100 wiper supporting head 14 and its supporting bar 15. This supporting bar 15 of the wiper head is reciprocally mounted in a slideway 16, formed in the opposite side of the block 8 from its hub portion 8^a.

The wiper head 14 projects beyond and over the slideway 16 of the block 8, and its under side is provided with a curved track

portion or filet 17, that extends from the under side of the head to the adjacent side of the bar.

This curved track portion 17 of the head 5 is engaged by a roller 18, that is rotatively mounted in the forked end of a vertically disposed rack bar 19, that is reciprocally mounted in the slideway block 12, that is provided with a partially inclosed and partially open slideway 20, in which the rack bar fits. This rack bar is provided with a vertical row of gear teeth along one edge, which register opposite to the open space of its slideway supporting block.

15 This toothed rack portion of the rack bar 19 meshes with a pinion 21 that is mounted loosely on a square shaft 22. The pinion is provided with a hub portion 23 that is adapted to be rotatively journaled in a bearing 24 on the slideway block 12, there being one of these blocks on each side of the center of the machine on which the two extension end wrapping mechanisms are secured. The hub of the pinion extends through the 25 bearing and a flange 25 is formed on it, which secures the pinion from lateral movement in its bearing. The square shaft extends across the center of the table and on opposite sides of it far enough to allow 30 these pinions and their bearings to be moved toward or away from the center of the machine to wrap the opposite ends of the different sized blanks on their respective different sized boxes.

35 One end of this square shaft extends to and through a bracket 26 that is secured to the adjacent side of the frame of the machine, and is journaled in a hub 27 that is formed on the bracket, and on its outer end 40 a pinion gear 28 is secured that meshes with a vertically reciprocating rack bar 29, which is slidably mounted in bearings 30 that are formed on a bracket 26, which is secured to the end of the table. The lower end of this 45 rack bar 29 is connected to one end of a reach bar 31, the opposite end of which is connected to the upper end of a forked lever 32, the opposite forked end of which straddles the main shaft 6. This lever is provided with a roller 33 that engages a cam 34 on the shaft 6, which imparts a reciprocal movement to said rack bar, and rotates the pinion, which turns the square shaft and the pinions 21 that raise the rack bars 19.

55 The arrangement of the rack bar 29 with respect to the reach bar 31, as shown in Fig. 1, is for wrapping boxes of the greatest depth of which the machine is capable of wrapping. The rack bar 29 is provided at 60 its lower portion with a slot 35 and a block 36 is bolted to the upper end of the bar 31, and is provided with a recess in which rests the lower end of the rack bar 29, and the bar is held within the recess by a cap 37. A 65 pin 38 passes through the lower end of the

rack bar 29 and bears against the lower end of the block 36, and an adjustable block 39 bears against the upper end of the block 36, and is secured to the rack bar 29 by a bolt 40 which passes through the slot 35. Thus 70 arranged, the cam fork 32, the reach bar 31 and the rack bar 29 move in unison, as will be understood, and with these parts thus arranged, as shown by Fig. 1, the end wipers are raised high enough to accomplish the 75 end wiping of boxes of the greatest depth for which the machine is set. In wrapping boxes of less depth, however, the rack bar must have a shorter stroke in order to diminish the rotative travel of the gear wheels 21, and to accomplish this, the adjustable block 39 is moved up a suitable distance above the block 36, and is firmly clamped to the rack bar by its bolt 40. Thus the movement of the cam 34 will raise the reach bar 80 31 a short distance before the block 36 engages the block 39, after which the rack bar and reach bar move up in unison.

Assuming that the reciprocal stroke of the bar has been properly adjusted to fit the height of the ends of the box between the extension edge and the end wipers, then it rotates the pinion 28 and the cross bar and its pinions 21 which reciprocate the rack bars 19 of the opposite box end wipers, and they cause each of these extension edge and end wrappers to act as follows:

The lower plunger block is of a size to extend to the outer edges of the side and end edges of the extension bottom of the 100 box. The hinged supporting block 8 is provided with a blank pressing blade 41 that is secured to it and that extends across its top and equally beyond its opposite sides, and is of the full width of the extension edge 105 of the end of the box, and the head of the wiper is provided with a stepped portion 42, on which a wiper block 43 is clamped by a clamping plate 44, that is secured to the top of the head 14 by a clamping bolt 45. This wiper block has its upper edge rounded 110 backward from its outside face, which with its rounded edge is covered with a pad of felt or other suitable soft cushioning material.

115 The end wipers are of the full width of the end of the box above its extension edge.

The bar 15 of the wiper supporting head is secured in its initial wiper starting position relative to the extension edge of the 120 presser blade by a spring 46 that is secured to the back of the block 8 at one end, and extends beyond its lower end and fits with a resilient bearing pressure into a recess 47 that is formed in the bar 15. Consequently 125 when the wiper head is down in the slideway of the block and resting on top of the block, it and its bar are secured by this spring with a spring tension to the block, and when in this position the wipers are 130

ready to engage the opposite ends of the box the instant the extension edge blank turning and presser blades act operatively on the end flaps of the blanks, and the extension end edges of the box, as will be presently described.

The opposite face of the wiper head bar 15 from the spring receiving groove 47 is provided with a projecting lug 48, and the toothed rack bar is provided with a recess 49 in its edge that is arranged in the path of and to receive the lug 48 at a predetermined point in its upward movement, which point is reached in the upward movement of the rack bar the instant the extension edge presser blades have completed their blank turning movement over the edge and top side of the extension edge of the box.

At the instant the blades have been tilted down hard against the upper surface of the extension edge and the end wipers have been moved straight against the end surfaces of the box, a projection on a cam 50 permits the sliding plates 13, with the wiper supporting slideway blocks 12, to be moved slightly inwardly, so that the wipers will be pressed firmly against the vertical end surfaces of the box by springs 51. This inward movement of the end wipers against the ends of the box is accomplished in the following manner:

Each of the slide plates 13 has a depending bifurcated lug 52 at its outer end, to which one end of a link 53 is pivotally secured, and the other ends of these links are connected to levers 54 and 55 respectively, which are rigidly secured upon shafts 56 and 57 respectively, which are mounted in the sides of the table. The lever 54 is a bell crank form of lever, and its other member is connected to the upper end of a rod 58, the lower end of which is secured to an eye bolt 59, which is secured in the end of one arm 60, of a double armed lever, the other arm 61 of which carries a roller 62, which is adapted to be engaged by a cam on the peripheral edge of the cam disk 50. The double armed lever is mounted on a stub shaft, which projects from a bracket 63, that forms an integral part of the cap of the adjacent bearing standard 64, which forms one of the supports for the main driving shaft 6. The pins which secure the links 53 to the lugs 52, extend beyond one side of each lug, as shown at 65, (Fig. 4) and to each of these pins is connected one end of a coil spring 51, the other ends of which are connected to pins 66, which are secured to the table 3. The outer ends of the shafts 56 and 57 carry respectively levers 67 and 68, the lever 67 extending upward, while the lever 68 extends downward, and the ends of these levers are connected by a rod 69. It will thus be seen that while the roller 62 rests upon the cam projection of the cam disk 50, the lever arms

60 and 61 are held in the position shown in Fig. 1, and the rod 58 prevents rocking of the bell crank lever 54, and the lever 55, under the pull of the contraction springs 51. But when the cam on the disk 50 passes 70 from under the roller 62, the levers 60, 61, are free to rock, and the pulling tension of the springs 51 upon the lugs 52 causes the slide plates 13, which carry the end wiper mechanism, to move inward so that the end 75 wipers will engage the folded end flaps of the blank and press them against the ends of the box under pressure represented by the tension of the springs 51, and this pressure is exerted while the wipers are moved upward against the ends of the box, so as to firmly press the gummed end flaps against the ends of the box. The movement of the bell crank 54 is imparted to the lever 55 through the medium of the connecting rod 80 85 69, which permits both springs 51 to act in unison, and which causes the levers 54 and 55 to move back in unison when the cam on the disk 50 again passes under the roller 62 and thereby lifts the rod 58. 90

As the plates 13 carry the wipers 43, it will be readily seen that the said wipers will be moved toward each other against the ends of the box, and with a resilient contact effected by the springs 51. 95

The operation of our combined box bottom extension edge and end wiper blank wrapping mechanism is as follows:

When the vertical rack bars 19 are moved vertically upward by the rotative movement 100 of the square shaft and the pinions 21, its roller 18, which normally bears up under and against the curved track member 17 of the head and its bar, pushes that member upwardly and swings them at the opposite 105 ends of the box supporting plungers up over their pivotal pins 9, which movement causes the blades 41 to engage the end flaps of the blanks and carry them over the extended edges of the ends of the box and carry them 110 down against the upper surface of the extension edges of the ends of the box and press them down tight up to and against the side corners of the extension edges, as these presser blades are made wide enough and are 115 arranged to fit close and to press the blank against and glue them into the corners and against the adjacent ends of the box.

At the same time these extension edge wrapping blades swing over onto the top 120 edges of the extension edge of the box, the blank end flaps and the box end wipers 43 are also swung up over and they also engage end flaps of the blank and carry it up against the ends of the box, but they do not 125 press hard enough at this time to prevent the blades from pressing the end flaps of the blank down tightly against the top of the extension edge of the box. These presser blades are actuated by the vertical rack bars to 130

press down hard against the top surfaces of the extension edges, and this pressure forces them firmly against the lower plunger, upon which the extension edges of the box rest. 5 Consequently the gummed blank is pressed and glued down tightly and smoothly against the top and corner surfaces of the ends of the box. When the rollers 18 of the vertical rack bars have swung the presser 10 blades over and down firmly against the top surface of the extension edges of the ends of the box they also swing the outer ends of the blade supporting block down between the ends of the yokes to which they are pivotally 15 secured, and against the sides of their respective rack bars, and the projecting lugs 48 of the bar extensions of the wiper supporting heads move into the recesses 49 of these rack bars, these several movements being formed 20 quickly and automatically as the rack bars move continuously upwardly, and they do not stop when the lugs swing into the recess 49 of the rack bars as the pinions 21 and shaft 22 are rotating continuously, and consequently the instant the presser blades have 25 made their wrapping and pressing movement against the top of the extension edges, the next instant the rack bars are continuing their upward movement, and they lift the bars 15 up with them, and their rollers 18 engage and bear against the outward curve track of the head portions, the springs 30 51 holding the wipers firmly against the ends of the blank which are thus pressed and glued against the ends of the box, and at the same time the rack bars which are still moving upward, lift the wiper bars and their heads and the wipers 43 with them and press 35 the end flaps of the blank, as they move up 40 the ends of the box, up against and glue them to the ends of the box. The rack bars then reverse their movement and move the wipers down, the said wipers having first 45 been moved slightly away from the ends of the box by the action of the cam 50. The wipers descend until the head 14 engages the swinging block 8, and instantly the lugs 48 on the bars 15 are disconnected from the 50 notches 49 of the rack bars, and as the rack bars continue their downward movement, the wiper supports swing by gravity to a horizontal position, and complete the wrapping of the extension edges of the ends and also the ends of the box above its extension 55 edge. The ends of the side flaps and also the end flaps of the blanks are left projecting far enough above the top ends of the box to allow them to be turned in by a special turn-in mechanism, which we do not illustrate, but which is fully illustrated and described in our pending application, Serial 60 Number 59,860, filed November 5, 1915, for an automatically operating multiple stage treatment box wrapping machine.

65 When it is desired to wrap the ends of

straight sided non-extension edge boxes with blanks by either the tight or loose wrap kind of box wrapping, the presser blades supporting blocks and the wiper heads and bars are removed with their yoke-shaped brackets 70 from the machine. The rollers are also removed from the ends of the rack bars 19, and suitable wiper head block and the wipers are secured to them by pinning them between and to the yoke ends of the rack bars. 75

Our invention provides a simple and positively operating mechanism for wrapping the ends of bottom extension edged boxes that act quickly and glues the end flaps of the blank neatly over the corner end flaps 80 of the blanks that were previously wrapped around the side corners of the box and glued to the ends of the box by the corner wipers; and while we have illustrated and described the preferred construction and 85 arrangement of our extension edge blank wrapping mechanism for the sides and especially for the opposite ends of extension edge boxes, we do not wish to be limited to the construction and arrangement shown, as 90 many changes might be made without departing from the spirit of our invention.

Having described our invention, what we claim as new and desire to secure by Letters Patent, is:

1. A mechanism for wrapping a gummed blank around an extension edge box, comprising a blank presser blade, a blank wiper movable with said blade into blank wiping relation to said box and then movable independent of said blade, and means for operating said blade and wiper to wrap the blank first around said extension edge and then against the adjacent surface of said box.

2. In an extension edge box and blank wrapping mechanism, the combination of a support for the box and its extension edge, the tilting presser blade carrying block, the wiper head and wiper slidably mounted therein, and means including a reciprocating rack bar for moving said presser blades and wipers to wrap the blank on the extension edge and the adjacent surface of the box.

3. A box bottom extension edge and gummed blank wrapping mechanism, comprising a support for the box and its extension edge, a blade carrying block pivotally supported to swing a predetermined distance over and into the extension edge of the box, a wiper supporting head reciprocally mounted in said block, a reciprocating rack bar arranged to engage and tilt said block so that its blade and said wiper fold said blank over and against the extension edge of said box and against its adjacent surface above said extension edge, and means whereby said rack bar holds said blade and blank down against the top sur-

face of said extension edge and at the same time moves said surface wiper upwardly and wraps and glues the blank against the surface of said box above its extension edge to 5 the top edge of said box, and means for reciprocating said rack bar.

4. A mechanism for wrapping the extension edge boxes with gummed blanks, comprising a yoke-shaped bracket, a presser 10 blade supporting block pivotally mounted to swing in said bracket, and means including a cam actuated reciprocating rack bar for moving said block to cause its blade to fold said blank over and against the top 15 surface of the extension edge of said box.

5. A mechanism for wrapping the extension edge boxes with gummed blanks, comprising a yoke-shaped bracket, a presser 20 blade supporting block pivotally mounted to swing in said bracket, a box end wiper device reciprocally mounted in said block and arranged to fold the blank against the end of the box, and means including a cam 25 actuated reciprocating rack bar for moving said block to cause its blade to fold said blank over and against the top surface of the extension edge of said box.

6. A mechanism for wrapping the extension edge boxes with gummed blanks, comprising a yoke-shaped bracket, a presser 30 blade supporting block pivotally mounted to swing in said bracket, a box end wiper device reciprocally mounted in said block and arranged to fold the blank against the end 35 of the box, means including a cam actuated reciprocating rack bar for moving said block to cause its blade to fold said blank over and against the top surface of the extension edge of said box, a recess in said 40 rack bar, a lug on said end wiper device arranged to register in said rack bar's recess after said blades have wrapped and glued said blank down against said extension edge, and arranged then to move said box end 45 wiper upward independent of said blade and wrappingly glue said blank to the ends of said box.

7. In an extension edge box wrapping machine, the combination with the wipers 50 that wrap the blanks to the surfaces of boxes above their extension edge portions, of the box extension edge wrapping mechanism comprising means including the tilting blades provided with a resilient cushioning 55 relief mechanism for pressing a blank against the top surface of the extension edge of a box.

8. In an extension edge box wrapping machine, the combination with the upper surface wipers of the box, of the box extension edge wrapping mechanism comprising means including the tilting blades provided with operative mechanism for pressing a blank 60 against the top surface of the extension edge of a box first, and the surface wipers ar-

ranged to then wrap the blanks against the surfaces of the box, and means including cam actuated mechanism for operating said blades to and from said box with a resilient yielding blank and box wrapping pressure on said box's extension edge. 70

9. An extension edge box and gummed blank wrapping mechanism, comprising an extension edge presser blade and a box surface wiper connected together by a resiliently separating connection arranged to move together to engage and wrap the opposite flaps of said gummed blank simultaneously against the top surface of the extension edge of the blade and against its opposite surfaces. 75

10. An extension edge box and gummed blank wrapping mechanism, comprising an extension edge presser blade and a box surface wiper connected together by a resiliently separating connection arranged to move together to engage and wrap the opposite flaps of said gummed blank simultaneously against the top surface of the extension edge of the blade and against its 80 opposite surfaces, said blades being arranged to wrap the flaps of the blank down against the top surface of the box extension edge and to stop there, means for moving said wipers to break its connecting resilient connection with said blades and for moving said wipers upwardly away from the downwardly pressing presser blades and wrappingly glue the ends of the blanks to the surfaces of the box above said blades, 85 means for slightly backing off said surface wipers and returning them to the blades and resiliently connecting them to said blades, and means for moving both blades and wipers simultaneously together away 90 from said box. 100

11. In a device of the character specified, the combination with a table having a reciprocating plunger mounted therein, of supports slidably mounted on said table, blocks 110 adjustably secured to said supports, frames on said blocks, normally horizontal slideway blocks in swinging engagement with said frames, having presser blades on their outer ends, bars slidably mounted in the 115 slideway blocks having wipers thereon which normally rest upon said presser blades, resilient means for normally locking said bars and said slideway blocks together, reciprocating means for swinging said slideway blocks to a horizontal position, whereby said presser blades overlap the opposite 120 ends of said plunger, means whereby the reciprocating means are locked to the wiper carrying bars when the said bars assume vertical positions, whereby the said bars with their wipers are moved upward and then back to their normal positions when the slideway block and parts carried thereby swing by gravity to horizontal positions, 125 130

and means for moving said slidable supports inward and then outward at predetermined periods.

12. In a device of the character described, 5 a support, a normally horizontal block in swinging engagement with said support, an extensive bottom presser blade on the outer end of said block, a bar slidably mounted in said block having an end wiper thereon 10 which normally rests on said presser blade, a reciprocating bar for engaging and swinging said block to a vertical position, means for locking said wiper carrying bar to said reciprocating bar when the wiper bar assumes a vertical position, whereby the said 15 wiper bar is moved upward by the further movement of the reciprocating bar, and then downward until the end wiper rests upon

the extension bottom presser blade when a further downward movement of the reciprocating bar unlocks it from the wiper bar, and the said block and parts carried thereby swing by gravity to a horizontal position, resilient means for normally locking the wiper bar to the swinging block, and resilient means for moving the said support in and out at predetermined periods. 20 25

In testimony whereof we affix our signatures in presence of two witnesses.
